UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

MOP HOLDER.

Application filed March 14, 1927. Serial No. 175,185.

My invention relates to mop holders of the type comprising a bar forming a handle portion provided at one end with relatively movable jaws between which the swab is releasably clamped, the movable one of the jaws being operatively connected with a pivoted lever which in jaw-closing position extends adjacent the bar.

My primary object is to provide a novel, simple and economical construction whereby accidental release of the pivoted lever from jaw-closing position, with consequent releasing of the swab, will be prevented.

Referring to the accompanying drawings: Figure 1 is a view in elevation of the mop-head portion of a mop constructed in accordance with my invention. Figure 2 is a section taken at the line 2 on Fig. 1 and viewed in the direction of the arrows; and Figure 3, a broken view in elevation of a portion of the structure shown in Fig. 1 and illustrating a modification of the retaining means for the lever.

Referring to Figs. 1 and 2, the mop therein shown comprises a bar portion 4 as is common in mop constructions provided at one end with a jaw member 5 rigidly secured thereto and presenting a groove 6 extending crosswise of the bar 4. Cooperating with the jaw member 5 is a movable jaw 7 shown as of general yoke form, the cross member 8 of which is movable into and out of a position in which it extends into the groove 6, these jaws being provided for rigidly securing in place a swab (not shown) clamped therebetween in accordance with common practice.

The ends 9 of the yoke 7 are pivotally connected with a lever 10 between the ends of the latter, this lever being pivotally connected at a loop 11 thereon with one end of a coil spring 12 surrounding the bar 4 and bearing at its other end against the jaw 5, the various parts being so constructed and arranged that when the lever 10 is rocked to the position shown in Fig. 1 the spring 12 will be compressed, thereby gripping the swab between the jaw members 5 and 8.

According to my improvement, the lever

10 is provided with means adapted to releasably engage the bar 4 when the lever is in jaw-closing position and retain the lever in this position against accidental displacement. These means preferably comprise spring arms 13 arranged at opposite lateral edges of the lever 10 and formed integrally therewith, these arms being bent into such a position that they will yield outwardly in swinging the lever 10 to the position shown and embracingly clamp the bar 4. These arms may be conveniently formed in the process of stamping the lever 10 into form from a sheet metal blank of any suitable material.

The construction illustrated in Fig. 3 is the same as that shown in the preceding figures except that instead of the clamping arms 13 being stamped from the blank from which the lever 10 is formed, they are formed from a separate piece of spring metal shaped 70 to present a substantially U-shaped member 14 which is riveted, as represented at 15, or otherwise suitably secured, to the lever 10 to extend transversely thereof and position its arms relative to the bar 4 as in the construction shown in Figs. 1 and 2 thereby yieldingly embracing the bar 4 when the lever 10 is in jaw-closing position.

It will be understood from the foregoing that my improved lever-holding means are not only of simple and economical construction, but serve to effectually hold the lever 10 against accidental displacement.

While I have illustrated certain forms of construction constituting embodiments of my invention, I do not wish to be understood as intending to limit it thereto, as the same may be variously modified and altered without departing from the spirit of my invention.

What I claim as new, and desire to secure by Letters Patent, is:

1. A mop-holder comprising, in combination, a bar, relatively-movable jaws on said bar, a pivoted sheet-metal lever adapted to effect relative movement of said jaws and in jaw-closing position extending adjacent said bar, and resilient spaced arms integral with

said lever and adapted to embracingly engage said bar and hold said lever in jaw-closing position.

2. A mop-holder comprising, in combination, a bar, relatively-movable jaws on said bar, a pivoted lever stamped from sheet metal and adapted to effect relative movement

of said jaws and in jaw-closing position extending adjacent said bar, and arms at opposite sides of said lever and adapted to embracingly engage said bar and hold said lever in jaw-closing position, said lever and arms being formed as a one-piece structure.

HENRY TSCHERNING.
